UNITED STATES PATENT OFFICE.

JAMES DENVER, OF NEW HAVEN, CONNECTICUT, ASSIGNOR OF ONE-HALF
TO THE NEW HAVEN CAR TRIMMING COMPANY, OF SAME PLACE.

CAR-BASKET RACK.

SPECIFICATION forming part of Letters Patent No. 309,033, dated December 9, 1884.

Application filed September 15, 1884. (No model.)

To all whom it may concern:

Be it known that I, JAMES DENVER, of New Haven, in the county of New Haven and State of Connecticut, have invented a new Improvement in Car-Basket-Rack Brackets; and I do hereby declare the following, when taken in connection with the accompanying drawing and the letters of reference marked thereon, to be a full, clear, and exact description of the same, and which said drawing constitutes part of this specification, and represents a perspective view.

This invention relates to an improvement in the racks, or what are called "baskets," in railway-cars—that is to say, the racks which are arranged near the ceiling in the car to receive packages, &c. In the usual construction these racks consist of a bracket at each end with a basket-like body between. While these racks or baskets afford convenience for holding packages, they are not properly fitted for hanging articles thereon, such as hats, &c. The object of my invention is to provide these racks with a device upon which hats and like articles may be conveniently hung; and it consists in constructing the bracket with a

vertically-projecting hanger, as more fully hereinafter described.

A represents the bracket which forms one end of the basket, and may be of any of the usual forms. At its front end I cast or attach thereto a hanger, B. This hanger is in the form of a vertical pin, and in shape as to conveniently receive a hat or thing to be hung thereon. Other shapes, however, may be employed, it only being essential that the hanger shall project from the bracket in such a manner that the hat or other article can be hung thereon without interference with the body of the basket.

I do not claim, broadly, a car-basket rack having projections thereon upon which articles may be hung.

I claim—

A railway-car basket constructed with an upwardly-projecting pin, B, substantially as described.

JAMES DENVER.
